WILLIAM TAYLOR AND FRANCIS WILLIAM PRESTON, OF LEICESTER, ENGLAND.

METHOD FOR PREPARING LENSES AND THE LIKE FOR GRINDING AND POLISHING.

1,358,676.

Specification of Letters Patent.

Patented Nov. 9, 1920.

Application filed August 18, 1920. Serial No. 404,450.

To all whom it may concern:

Be it known that we, WILLIAM TAYLOR, a resident of Leicester, in the county of Leicester, England, a subject of the King of Great Britain, and FRANCIS WILLIAM PRESTON, a resident of Leicester, in the county of Leicester, England, a subject of the King of Great Britain, have invented certain new and useful Improvements in Methods for Preparing Lenses and the like for Grinding and Polishing, of which the following is a specification.

This invention relates to improved methods for mounting lenses and the like in preparation for grinding and polishing operations, and is particularly directed to methods of conditioning the binder by means of which the lenses are mounted.

This application is a continuation in part 20 of our previous application Serial No. 357,865, filed February 11, 1920.

In the production of lenses and like objects (all of which will hereinafter be referred to as "lenses") having a surface or surfaces requiring grinding and polishing, it is usual, during the grinding and polishing operations, to protect the rear surface of the lens by means of an adherent mass of cementitious or binding material which 30 on the one hand, if a lens is to be worked singly, may be made to serve as a holder or handle; and which on the other hand, if the lenses are to be manufactured in quantity, will enable a number of lenses to be assembled and attached to a single rigid holder so as to form a "block" such that all the lenses of the block can be ground and polished together.

The cementitious or binding material employed may be a compound capable of being softened by heat, and in such case usually comprises a bituminous substance and a stiffening agent. Of these, the bituminous substance may be coal-tar pitch, wood-pitch, 40 natural bitumen of suitable quality, or any similar substance or mixture (all of which are hereinafter referred to as "pitch"); while the stiffening agent, which is incorporated with the pitch, may consist of 45 finely-divided mineral matter such as wood-ash, yellow-ocher, or other substance which, in addition to stiffening the mixture, is adapted to reduce the thermal expansion of the mass and capable (if of suitable character for such purpose) of increasing its 50 thermal conductivity. A composition which

has been found satisfactory in practice comprises the following proportions by weight:—

Coal-tar pitch	2 parts.	60
Wood ash	1 part.	

Such a compound of pitch and a stiffening agent will be referred to hereinafter as a "binder," but it should be understood that 65 by the use of this term we do not intend to limit ourselves to a binder of the particular composition which has been stated by way of example.

Investigation has shown us that the 70 binder thus constituted should possess the property of being, at ordinary temperatures, what may be termed "self-annealing"; by which term is meant the property by reason of which the stresses set up in the mass 75 of binder during cooling and shrinking become relieved within a comparatively short space of time after the binder has set. When this property exists, it is found that although, after being applied to a lens, the 80 binder cools and shrinks so as to produce in the lens a distortion which may continue for some minutes, yet within (say) half an hour the strain is relieved and the lens becomes free from distortion. This desideratum 85 may be fulfilled by the binder in its initial state, but we have ascertained by means of polariscope tests that, with the method of treatment hitherto followed, the self-annealing property has not been maintained for any length of time. That is to 90 say, heretofore, it has been the usual practice to keep the binder melted in open vessels (commonly known as pitch-pots at a general temperature of about 110 to 120 degrees centigrade; under which conditions 95 there is slowly driven-off a mixture of volatile oils so that the binder gradually deteriorates and becomes harder, losing its self-annealing property. This deterioration is 100 aggravated by heating the pot with a gas flame in such a way that the temperature of the binder may locally exceed, by a considerable amount, the temperature just named. In consequence of this deterioration, 105 the lenses to which the binder is applied not only become distorted as the binder cools and shrinks upon them, but remain distorted throughout the grinding and polishing operations, with the result that the 110 final accuracy of the lenses is seriously affected. Frequent disturbance, or ruptur-

ing of the surface, of the molten binder in the pitch-pot by stirring, accelerates the deterioration.

Investigation has shown us that, concur-
rently with the loss of volatile oils, there
occurs a gain in weight which compensates
to some extent the loss of weight due to
the volatilization of the oils and which prob-
ably represents the effect of oxidation con-
sequent on exposure to the atmosphere. The
changes thus produced are irreversible; and
although the binder may be re-softened by
the addition of green (anthracene) oil, it
does not, after such re-softening, exhibit its
original qualities.

According to the present invention the
binder, constituted as above described and
preferably having a content of stiffening
agent as high as is compatible with reten-
tion of the above-mentioned self-annealing
quality, as for example, a content of stiff-
ening agent amounting to one-half the
content of pitch by weight is, during use,
kept melted in a closed vessel at a tempera-
ture which does not materially exceed that
at which destructive change occurs in the
composition of the binder; the molten
binder being preferably stirred continuously
(without exposing it to contact with the
atmosphere) in such manner that uniform
distribution of the heat is promoted and
segregation of the constituents of the binder
is prevented. For this purpose the closed
vessel may be provided with a steam-jacket
(or other heating device) and means for
supplying thereto steam (or other heating
agent) at a suitable temperature, a mechani-
cal stirring-device and means for continu-
ously actuating the same, and a gate-con-
trolled outlet which may also be steam-
jacketed (or otherwise heated) so as to in-
sure the maintenance of fluidity up to the
point of discharge of the binder from the
vessel.

45 The temperature within the closed vessel
should be raised only so far (to about 130
or 140 degrees centigrade) as to insure in
the binder such fluidity as is necessary for
enabling it to be poured and molded with
facility; this temperature, while somewhat
higher than that usually employed with
an open pitch-pot, being not too high when
used with a closed vessel wherein the risk
of deterioration (owing either to volatili-
50 zation of the oils or the presence of traces
of atmospheric air) is minimized, and being
moreover sufficiently low both to obviate
injury to the lenses to which the binder
is applied, and also to expedite the subse-
quent cooling of such lenses to ordinary
60 room-temperature.

We have found that the binder, prepared
as described, is capable of retaining its self-
annealing property for an indefinite period
65 of time. It may be employed for holding

lenses in any manner; for example, whether
the binder is applied to the lenses either
singly or when the lenses are assembled,
or to be assembled, in a block; whether or
not the binder is brought to shape in a mold; 70
also whether the binder is applied first to
the lenses, which are then attached to a
holder, or first to the holder in the form of
a layer to which the lenses are subsequently
attached. The binder may be applied in 75
the molten condition directly to the surface
of the lens, or may be initially formed into
a pellet the surface of which is subsequently
heated so as to cause it to adhere to the
lens to which it is applied. Before the ap- 80
plication of the binder, the lens may be
warmed, and its surface may be coated with
a sticky composition (known in the indus-
try as "tacky") whereby adhesion between
the lens and binder is increased. The 85
binder, if required to be molded, may be
brought to shape in a mold whereof one
wall is constituted by the lens to which the
binder is to be made to adhere, the mold
being adapted to confine the binder within 90
the area of the lens; while distortion of the
lens may be obviated by reducing the thick-
ness of the molded mass of binder through-
out a portion of its area, or by placing a
layer of non-adhesive material upon the 95
center of the surface of the lens before the
binder is poured into the mold.

In the accompanying drawings, Figures 1
and 2 illustrate, in side elevation and plan
respectively, one form of apparatus for
heating and conditioning the binder, for 100
delivering it to lenses in molds, for closing
the molds, and for coating the surface of
each lens with "tacky" previous to the ap-
plication of the binder. Fig. 3 is a side ele- 105
vation partly in axial section, of one of the
molds seen in Figs. 1, and 2, (but drawn to
a larger scale) together with the plunger
which constitutes the closure for the mold;
a bi-convex lens being shown in position in 110
the mold. Fig. 4 is a partly sectional side
view of a bi-convex lens with the molded
mass of binder adherent to it. Fig. 5 is a
view similar to Fig. 4, but showing a con- 115
cave lens and means for preventing adhe-
sion between the binder and the lens at the
center of the latter. Fig. 6 is a side eleva-
tion of a convenient form of "tacky" spray-
nozzle.

11 (Figs. 1 and 2) is the hollow body or 120
container of a mixing machine, of well
known type, which we find suitable for use
in heating and conditioning the binder, the
container being provided with a steam
jacket 12 supplied with steam through a 125
pipe 13, while 14 is a pipe for draining
water of condensation from the jacket. We
provide the container 11 with a removable
cover 15 and with a hopper 16 for the intro-
duction of fresh binder into the container, 130

the hopper being normally closed by a cover 17. A pair of rotary paddles 18, 18 mounted on shafts 19, 19 serve to stir up the binder within the container 11; the shafts 19, 19 being geared together and adapted to be continuously driven by suitable means (not shown). A steam-jacketed pipe 20 leads from the interior of the container to the point whereat the binder is to be delivered to the molds, this pipe terminating in an obliquely-chamfered dependent nozzle 21 the passage between which and the pipe itself is controlled by a screw-down valve 22 for regulating the rate of delivery of the binder.

By suitably adjusting the pressure of the steam within the jacket 12, the binder within the container 11 may be kept at the desired temperature without appreciable deterioration or loss of important volatile constituents, the conservation of which is assisted by the container being closed; while the continuous action of the paddles 18 serves to keep the mass of binder thoroughly homogeneous and uniform in temperature throughout.

The mold A shown in detail in Fig. 3 comprises a base portion 23 surmounted by a circular ledge 24 presenting at its inner side a seating 25 of a diameter to receive and hold the lens to which the binder is to be applied, the lens being supported around its margin only, while over the outer side of the ledge 24 is removably fitted an annular inwardly-conical cap 26 which, rising above the upper surface of the lens, forms a coaming adapted both to retain the lens in position within the mold and also to confine the binder laterally during the molding operation. The plunger B which forms the closure for the mold is adapted to be brought into operative position, after the mold has been filled with binder, by downward movement in the direction of the common axis of the mold, lens and plunger, and, in the example illustrated, comprises an annular rim 27 adapted to contact with the upper edge 28 of the cap 26 and a central circular projection 29 which, by entering the mass of binder bounded by the cap, forms in said mass a central depression 30, so that the binder 31 which adheres to the lens 32 when the latter is removed from the mold presents in axial section the profile shown in Fig. 4.

In order to facilitate the molding of the binder upon a number of lenses in succession, a number of molds A are detachably mounted upon a horizontal turntable 33 fitted to revolve about a fixed vertical stud 34 and provided at equal intervals with upright pegs 35 (Fig. 2) adapted to enter holes 36 (Fig. 3) in the base portions 23 of the several molds; the turntable 33 being rotated step-by-step through angular inter-

vals corresponding to those separating the pegs 35. For this purpose, in the example illustrated, the turntable 33 has on its lower side a dependent annular flange 37 in which are formed a series of radial grooves 38 opening out at both the external and internal peripheries of the flange; these grooves, which are spaced apart at angular intervals corresponding to those between the pegs 35, being engaged in succession by a pair of crank pins 39 (carrying antifriction rollers) which project vertically from a disk 40 fast on the upper end of a vertical shaft 41 revolved at a suitable speed by any convenient means (not shown). The shaft 41 may be continuously driven through frictional gearing so as to permit of any convenient means (not shown) being employed for arresting the rotation of the turntable 33 periodically during the intervals when successive molds are being dealt with.

As seen in plan, Fig. 2, the turntable 33 is to be understood as intended to be revolved contra-clockwise so as to bring successive molds A, first, under a spray-nozzle 42 for delivering "tacky" on to the upper surface of each lens 32 in its mold, secondly, under the nozzle 21 through which the binder is delivered, and thirdly under the plunger B which serves as a closure for all the molds in succession. The "tacky" may be ejected by any convenient means, for example by a pneumatically-operated device such as is commonly employed for spraying paint, varnish or the like.

The plunger B, which is shown in Fig. 1 as detachably fixed on the lower end of a vertical spindle 43 so as to be changeable to suit different molds, is actuated by sliding the spindle 43 through a stationary guide 44 supported on a bracket 45 extending from the fixed stud 34 about which the turntable 33 revolves; the upper end of the spindle 43 being connected by a link 46 to a hand-lever 47 fulcrumed at 48 to the bracket 45. The spindle 43 may be normally retained in the raised position, so as to hold the plunger B clear of the molds A, by means of a coiled spring housed within the guide 44 but not shown in the drawing. As the plunger is depressed by means of the lever 47 until arrested by the rim 27 encountering the edge 28 of the mold-cap 26, the surplus binder escapes over the edge 28. After the binder has set to the shape given to it by the mold and plunger, the plunger is raised and the lens 32 with its adherent mass of binder can be removed from the mold. The central depression or cavity 30 formed in the mass of pitch, (see Fig. 4) leaves only an annular rim 30 of pitch by which alone in such case the lens is subsequently attached to the holder for grinding or polishing.

While in describing the new method which constitutes the present invention, the compo-

sition of a binder which may advantageously be treated by the method has been stated by way of example, it should be clearly understood that the invention is by 5 no means limited to treatment of the binder whose composition has been set out by way of example.

What we claim and desire to secure by Letters Patent is:—

- 10 1. The method of preparing lenses and the like for grinding and polishing, which consists in heating a mass of cementitious material, having the property of self-annealing when cold and containing an ingredient which is capable of being softened by heat and liable to destructive change when heated above a certain temperature, to a temperature which will render it fluid, maintaining the mass in a fluid condition in a 15 closed vessel, at a temperature which does not at any point in the mass exceed the temperature at which such change occurs, to retain the self-annealing property of the material, and successively withdrawing 20 small quantities from the mass and applying them to the lenses to form backings upon the lenses.
- 20 2. The method of preparing lenses and the like for grinding and polishing, which 30 consists in heating a mass of cementitious material consisting chiefly of pitch, having the property of self-annealing when cold, to a temperature which will render it fluid, maintaining the mass in a fluid condition 35 in a closed vessel at a uniform temperature which does not exceed the temperature which will cause destructive changes in said pitch while continuously stirring the mass so as to cause even distribution of the heat 40 throughout the mass and prevent segregation of the constituents of the material, so that the self-annealing property of the pitch is retained, and successively withdrawing small quantities from said mass and applying 45 them to the lenses to form backings for the lenses.
3. The method of preparing lenses and

the like for grinding and polishing, which consists in heating a mass of cementitious material consisting chiefly of pitch, having 50 the property of self-annealing when cold, to a temperature which will render it fluid, maintaining the mass in a fluid condition in a closed vessel at a uniform temperature of about 130° to 140° C., while continuously 55 stirring the mass so as to cause even distribution of the heat throughout the mass and prevent segregation of the constituents of the material, so that the self-annealing property of the pitch is retained, and successively withdrawing small quantities from 60 said mass and applying them to the lenses to form backings for the lenses.

4. A method of preparing a plurality of lenses for mounting in block, which consists in bringing a mass of binding material 65 into fluid condition by the application of heat, and maintaining the mass at a uniform temperature and uniform consistency while successively withdrawing small quantities 70 from said mass and applying them to the lenses so as to form uniform backings for the lenses.

5. A method of preparing lenses and the like for mounting in block, which comprises 75 bringing a mass of binding material into fluid condition by the application of heat, maintaining the mass at a uniform temperature and of a uniform consistency while successively withdrawing small quantities 80 from the mass, and molding them upon the back of the lenses.

6. A method of preparing lenses and the like for grinding in block, comprising bringing a mass of pitch into fluid condition by heat, and maintaining said mass of 85 a uniform consistency by maintaining it at a uniform temperature in a closed vessel and continuously stirring it, while successively withdrawing small quantities from 90 the mass and molding them upon the backs of the individual lenses.

WILLIAM TAYLOR.

FRANCIS WILLIAM PRESTON.
